COMBINED DOOR KNOB AND ROSE

Charles A. Ellis, Hamden, Conn., assignor to Sargent & Company, New Haven, Conn., a corporation of Connecticut

Application June 4, 1954, Serial No. 30,802

Term of patent 14 years

(Cl. D10—8)

Fig. 1.

Fig. 2.

Fig. 1 is a side elevational view of a combined door knob and rose embodying my new design;

Fig. 2 is a top plan view thereof; and

Fig. 3 is a view partly in section on line 3—3 of Fig. 2.

I claim:

The ornamental design for a combined door knob and rose, substantially as shown.
